BOWLING BALL RETURN AND STORAGE RACK

John M. Ernst, Shelby, Ohio, assignor to American Machine & Foundry Company, a corporation of New Jersey

Application January 6, 1956, Serial No. 557,732

5 Claims. (Cl. 273—49)

This invention relates to bowling alleys, and more particularly to a novel bowling ball storage rack.

It is common practice in the construction of bowling alleys to provide a bowling ball storage rack at the approach or players' end of the alley, the balls being returned to such rack via a return runway which extends for the length of the alley. In bowling alley installations of the type usually constructed prior to the present invention, such storage racks have ordinarily been designed in such fashion that the rack extended generally in the direction of the alley, the rack being positioned between two adjacent alleys. Prior art workers have long recognized the desirability of constructing a bowling ball rack in such fashion that the portion of the rack supporting the balls would extend transversely of the alley in such manner that one desiring to take a ball from the storage rack would only have to approach the transversely disposed rack from an area behind the players and would never have to encroach upon the playing area. While such transversely extending bowling ball storage racks have heretofore been proposed, they have never been completely satisfactory for commercial use and accordingly were not adopted in the trade prior to the present invention.

An object of the present invention is to provide a novel bowling ball storage rack wherein all of the balls to be stored in the rack are supplied thereto via a single infeed means, to be disposed between two adjacent alleys, the balls discharged from such input means being diverted laterally therefrom onto one or another of a plurality of storage arms or tracks extending laterally of the input means and therefore generally transversely of the alleys.

Another object is to devise such a ball storage rack comprising novel and particularly effective means for diverting the balls from the single infeed means to the storage arms.

A further object is to provide a novel bowling ball storage rack including a single infeed track to be disposed between two adjacent alleys, a pair of laterally extending storage tracks, and means for diverting the balls from the infeed track to the storage track, the storage tracks and the infeed track being arranged generally in the form of a T, so that when the rack is installed, each of the storage tracks will project transversely behind the approach or players' portion of a different one of the two alleys between which the infeed track is disposed.

Yet another object is to devise such a storage rack wherein the diverter means is of very simple construction involving no moving parts, yet will be effective to provide a positive, dependable diverting action, assuring that all balls supplied to the rack come to rest in one or another of the laterally projecting storage tracks.

With these and other objects not specifically mentioned in view, the invention consists of certain combinations and constructions which will be hereinafter fully described and defined in the claims hereunto appended. In order that the manner in which these objects of the invention are accomplished can be understood in detail,

2

reference is had to the accompanying drawings, which form a part of this specification, and wherein:

Fig. 1 is a side elevational view, partly in section, illustrating a bowling alley provided with a ball storage rack constructed in accordance with one embodiment of the invention;

Fig. 2 is a plan view of two adjacent bowling alleys constructed in the manner illustrated in Fig. 1 and both served by a single ball storage rack in accordance with

10 the invention, Fig. 2 being on a smaller scale than Fig. 1;

Fig. 3 is a plan view, on a larger scale than Fig. 1, illustrating the bowling ball storage rack of Fig. 1;

Fig. 4 is a sectional view taken on the line 4—4, Fig. 3, with some parts shown in elevation;

15 Fig. 5 is a sectional view taken on line 5—5, Fig. 3, with some parts shown in elevation;

Fig. 6 is a sectional view taken on line 6—6, Fig. 3, with some parts shown in elevation;

Fig. 7 is a sectional view taken on line 7—7, Fig. 3, 20 with some parts shown in elevation, and

Fig. 8 is a view taken on line 8—8, with parts shown in elevation.

Referring to the drawings, Figs. 1 and 2 disclose a preferred embodiment of the invention installed in connection with a bowling ball return of the type described

25 and claimed in my divisional application Serial No.

700,064 filed December 2, 1957. The bowling ball return illustrated comprises a down sweep section designated generally at 20, a substantially horizontal track

30 or ball runway indicated generally at 22, and an up sweep section designated generally 24, the return being

arranged to deliver balls to a ball storage rack 26.

As fully described in the aforementioned divisional application, balls are supplied to the down sweep return

35 runway section 20 by a ball lifting apparatus indicated

generally at 25. The balls roll down section 20, along

the horizontal section 22, which is disposed beneath the

alley floor, and up section 24.

The upper end of up sweep section 24 (Fig. 1) is connected to ball storage rack 26 by a crest member 46.

This member comprises two suitably curved parallel spaced ball supporting guide rails, which in the illustrated embodiment, are formed of rods 48. These rods preferably are covered with a resilient material such as rubber,

which provides frictional contact for balls, and also functions to deaden the sound of balls rolling off up sweep

45 section 24 and along rods 48 en route to T storage rack 26. Tubes 48 at one end are connected by studs to a suitable bracket 52 mounted on the upper end of member

40 of up sweep section 24 and a pair of upright supporting plates 54. The other ends of rubber covered tubes

50 48 are secured by means of a pair of studs to a track section 58 which connects the crest member 46 with the stem of T storage rack 26.

Track section 58 preferably is slightly downwardly inclined from the point of its jointure with crest member

46 to the point of its attachment to T storage rack 26 and is attached to a suitable bridge bracket 60 secured at

60 its ends to upright supporting plates 54. Track section 58 is also supported by another bracket 62 attached to

the leading end of substantially horizontal track 64. Track 64, which constitutes the ball receiving stem or

65 track of T-shaped storage rack 26, is supported by and mounted between upright plates 54 which also serve as a housing or frame for T storage rack 26.

Despite the fact that a ball travels well over sixty

feet from the time it is delivered or placed on ball delivery track 34 until it rolls along up sweep 24 and onto

crest member 46, it still has considerable energy and

therefore in most instances it is desirable to provide

means for retarding or checking its movement before it

rolls along track 64 so that it may come to an ultimate

position of rest on one of the arms 75 or 77 of the head of the T designated 66. For this reason, a suitable ball check 63 is provided. Ball check 63 has a ball engaging arm 65 which extends upwardly through an opening in track member 58 in position to be engaged by a rolling ball, the speed of which is retarded thereby as desired for further slow rolling movement to its storage position on track 66. Ball check 63 may be similar in construction and operation to that disclosed in Zuercher application, Serial No. 549,832, filed November 29, 1955, now Patent Number 2,857,162, issued October 21, 1958. Since the details of the ball check do not form a specific part of the present invention, further description and disclosure thereof are omitted in the interest of brevity.

As shown in Figs. 2 and 3, track 64 is positioned at right angles with the center section of track 66 which forms the head of the T of my novel ball storage rack. Track 66 in its center position is secured to and supported by an upright column 68 and on its end portions by suitably shaped end supports or columns 70 (Figs. 3, 4 and 5). Track 64 is formed with a ball trough 72, the edges of which are parallel and form continuations of the ribs 57 of member 58, along which a ball rolls towards the head of T storage rack or track 66. Track 66 is provided with a pair of tapered troughs 74 extending in opposite directions from the center of the track to the ends thereof. The side edges of trough 74 taper or diverge from the center portion of track 66 towards the ends thereof towards rubber buffers 80. See Figs. 2 and 3. This arrangement is provided for the purpose of further slowing down the movement of a ball or absorbing its momentum as it moves to a position of rest on the head of the T storage rack.

Track 64 or the stem of the T storage rack may be formed integrally with track 66 or the head of the T storage rack. In the illustrated embodiment, these members are shown made up of separate units suitably attached to each other with the stem 64 located at right angles to and centrally of the head track 66. At the point of their interconnection, ball controlling members 76 and 78 are provided. In the form illustrated, these members are molded rubber inserts or sections which not only deaden the noise of balls moving on or striking these members, but also prevent damage to balls and absorb shocks of impact of balls striking them. One of these is a generally T-shaped member 76 serving as a connector and switch plate since it is fitted into both tracks 64 and 66 where it can direct an incoming ball from tracks 64 into one or the other of the two tapered ball troughs 74 in arms 75 and 77 of track 66. Switch plate 76 is located in the center portion of track 66 between troughs 74 of track 64 and serves as an entrance guide therefor. As shown in Figs. 3, 6, 7 and 8, member 76 works in conjunction with a molded rubber wedge shaped member 78 also located in the center portion of track 66. Member 78 serves as a bumper and deflector for balls rolling off trough 64 into track 66. The free end of each trough 74 of track 66 is provided with a suitably shaped end bumper 80, preferably of molded rubber, which prevents balls from rolling off the ends of troughs 74.

The stem portion of T-shaped switch member 76 is axially aligned with trough 72 of track 64 at the end thereof, so that a ball rolling along track 64 passes onto the stem portion of member 76. The cross bar of the T of member 76 is aligned with troughs 74 of arms 75, 77 of track 66 and includes two surfaces 79 and 81 slanting downwardly each into a different one of the troughs 74, as best seen in Figs. 3 and 6. The portion of member 76 between surfaces 79 and 81 is of course small as compared to the size of a bowling ball and is centered with respect to the nose of bumper and deflector 78.

When a ball rolls from track 64 onto switch member 76, at a time when troughs 74 are empty or when there

is no ball in either trough 74 at a point immediately adjacent switch member 76, the ball will usually strike the narrow nose of bumper and deflector 78 slightly off center, and will therefore roll down one or the other of tapered surfaces 79, 81 into the corresponding one of the troughs 74. Even should the ball happen to be perfectly centered with bumper and deflector 78 when it strikes the same, the ball will still roll down one or the other of tapered surfaces 79, 81, since, as will be clear from Fig. 3, these tapered surfaces are spaced so closely together that the ball will not balance therebetween.

The distance between the center of switch plate 76 and each bumper 80 is made such that troughs 74 will be completely filled by a predetermined number of balls and, when the last ball of that predetermined number comes to rest in one of the troughs 74, such last ball will occupy a space closely adjacent the switch plate. Then, when the next ball arrives on track 64, it will be cammed off and deflected into the opposite trough, either by contact with the adjacent ball in the full trough 74, or by contact with such adjacent ball and the bumper and deflector 78, assuming of course that the opposite trough is not occupied by its full complement of balls.

Thus, if arm 75 of track 66 contains its limit of, say, four balls, while arm 77 contains less than four balls, the ball in arm 75 nearest switch member 76 will be positioned to be lightly engaged by the next ball rolling along track 64, and the rolling ball will accordingly be deflected down tapered and slanting surface 79 into the trough 74 of arm 77. Similarly, if arm 77 is full when arm 75 contains less than its full complement of balls, the ball in arm 77 nearest switch member 76 is in position to deflect the next ball into the trough 74 of arm 75.

Molded rubber members 76, 78 and 80 are provided with a number of rubber plugs or projections 82 which engage tightly with suitable holes or indentations in track 66 for holding them in operating position. This mounting, however, permits easy replacement when and if necessary. In order to provide additional rigidity to bumper 78, the latter is backed up by a suitable post 84 secured to vertical supporting column 68.

The novel under alley or subway ball return and ball storage rack, as illustrated in Figs. 1 and 2 of the drawings, is shown in use with two adjacent bowling alleys A and A'. It is designed to serve both alleys so that balls B removed from either pit P or P' on alley A or A', respectively, may be returned to a bowler in minimum time. As mentioned hereinabove, a suitable elevating ball mechanism 25, such as disclosed in Holloway et al., Serial No. 170,162, now Patent No. 2,776,138, may be used to elevate balls delivered out of either pit P or P' onto common ball delivery track 34. This track, as well as the ball elevating device 25, as shown, are located in the space between two adjacent kickbacks K with two vertical plates 86 attached thereto to support the various components. Each kickback K is provided with a suitable opening H through which a ball may be ejected or roll from its respective pit into the range of operation of belt 27 of ball lifting device 25.

The use of an automatic ball lifting device, such as device 25, with the under alley ball return and the ball storage rack which constitute the invention, insures that every ball delivered onto rails 34 will have the same speed so that there is little or no danger of a ball coming to rest between the down sweep and up sweep section of the track, or of not having sufficient energy to roll up sweep 24.

What I claim is:

1. In a storage rack for bowling balls, the combination of an infeed track constructed to be mounted in a position to receive bowling balls from the return runway of a bowling alley and along which such balls can roll to a delivery end; storage track means extending gen-

erally transversely of said infeed track adjacent the delivery end thereof, said storage track means including two ball storage portions each extending outwardly from a different side of said infeed track, said infeed track and storage track means being dimensioned to operatively accommodate bowling balls; and fixed ball diverter means, other than such bowling balls, positioned in the path of travel of balls from the delivery end of said infeed track, said ball diverter means including a plurality of ball-directing surfaces disposed to be directly contacted by bowling balls travelling from the delivery end of said infeed track, at least one of said surfaces being directed toward each of said ball storage portions, said ball-diverter means being effective to direct the bowling balls from said infeed track, including the first ball delivered by said infeed track, at random to one or the other of said storage portions until said storage track means has been filled with balls, said ball-directing surfaces each substantially maintaining its normal stationary position throughout the ball diverting operation of said ball-diverter means.

2. A bowling ball storage rack in accordance with claim 1 and wherein said ball-diverter means comprises a stop spaced from the delivery end of said infeed track in the direction of travel of balls delivered therefrom, and diverter track means disposed between said stop and the delivery end of said infeed track, said diverter track means including opposed downwardly slanting surfaces each leading toward a different one of said storage portions, the combination of said slanting surfaces being short as compared to the length of said storage track means.

3. A bowling ball storage rack in accordance with claim 2 and wherein said diverter track means comprises a resilient generally horizontally disposed plate having a central portion aligned with the longitudinal axis of said infeed track and a pair of opposed surfaces extending outwardly and downwardly from said central portion, each of said opposed surfaces leading toward a different one of said ball storage portions.

4. In a bowling alley installation having a return runway, the combination of a bowling ball storage rack comprising a single infeed track disposed to receive bowling balls from the return runway and along which such balls can roll to a ball delivery station; ball diverter means; means fixedly mounting said ball diverter means at said ball delivery station in alignment with said infeed track; and two ball storage tracks each disposed on a different side of said ball diverter means and extending laterally with respect to said infeed track, said infeed and ball

35
40
45
50

storage tracks having dimensions for operatively accommodating bowling balls, said ball storage tracks each including a ball-receiving end portion disposed at said delivery station and below said infeed track, said ball diverter means comprising two opposed downwardly slanting surfaces each leading toward a different one of said ball storage tracks and the length of each such slanting surface being short as compared to the length of the one of said ball storage tracks to which it leads, said ball diverter means also including a stop spaced across said downwardly slanting surfaces from said infeed track, said slanting surfaces and said stop being fixedly mounted and disposed to be directly contacted by bowling balls delivered to said delivery station by said infeed track and being effective to direct the bowling balls from said infeed track, including the first ball delivered thereby, at random to one or the other of said ball storage tracks until both of said storage tracks are filled with balls, said slanting surfaces and said stop each substantially maintaining its normal stationary position throughout the ball diverting operation of said ball diverter means.

5. Apparatus in accordance with claim 4 and wherein said ball storage tracks are substantially equal in length, the distance from the center line of said infeed track to the end of each of said ball storage tracks being approximately equal to $ND + X$, where

N =the number of balls that can be stored on one of said storage tracks

D =the diameter of the bowling balls to be accommodated, and

X =a distance less than the radius of such bowling balls.
